UNITED STATES PATENT OFFICE.

MINO PELIZZOLA, OF MILAN, ITALY.

DISTRIBUTION FOR ROTARY ENGINES.

1,355,907.

Specification of Letters Patent. Patented Oct. 19, 1920.

Application filed January 28, 1919. Serial No. 273,693.

To all whom it may concern:

Be it known that I, MINO PELIZZOLA, a subject of the King of Italy, and residing at Milan, Italy, (whose post-office address is 5 Corso Genova No. 28,) have invented certain new and useful Improvements in or relating to the Distribution for Rotary Engines, of which the following is a specification.

10 The present invention relates generally to rotary engines as steam machines, pumps, hydraulic motors, air compressors, fans, adjustable brakes, counters and the like, and has for its object to supply a suitable automatic valveless distribution.

15 Some devices of this class have been previously described in the technical literature, but only by way of proposing geometrical problems or as examples of the various combinations of rotary or curvilinear or swinging link crank gear.

20 The absence thus far of practical embodiments of such designs has been due to the fact that no satisfactory method had been devised heretofore for the fluid distribution in such engines, this being in the present case closely connected with the engine construction itself.

25 The present invention solves the problem 30 at issue by realizing a perfectly automatic distribution, whereby the fluid at the inlet is always maintained sharply separated from the fluid at the outlet and this without the intermediary of any valves.

35 The annexed drawing (Figures 1-2-3-4) shows in front and rear view and in cross vertical and horizontal sections an example of the novel distribution as applied to one of the said engines used as a pump.

40 Figs. 5 and 6 show two other examples of actuation of the invention.

I wish it to be understood that the same engine—without altering its general construction, except a few constructional modi-

45 fications that will be obvious to any skilled in the art can be used for all the purposes referred to above. Since, as already observed, the distribution under report is closely connected with the engine construc- 50 tion, the various parts of the engine requiring to be designed to suit the distribution at issue in order that the latter can be realized, it follows that, when one of the said engines is described, also the distribution forming

the object of the present invention is simultaneously described. 55

1 indicates a barrel internally shaped in the form of two cylindrical coaxial chambers, separated by the annular projection 17. The size of this projection may be varied 60 according to the position of the diaphragm 18 with respect to the midline —f— of ring —11— while according to the drawing (Fig. 3) the diaphragm 18 is arranged on the midline of ring 11 and said midline 65 —f— is designed to be placed at the midline —h— of the cylinder 1, a displacement of said parts can be adopted; in this case the width of the ring —11— must vary accordingly. A bushing 5 projects from the 70 outer surface of the cylinder —1— while within said bushing the crankshaft 6 rotates. In the front wall of the cylinder 1 two openings 7 and 8 are provided, being the inlet and outlet openings for the fluid 75 respectively drawn from or forced into the ducts 9 and 10, the machine being reversible.

The half crescent shape of the openings 7 and 8 determines the system of the automatic distribution, as explained hereinafter. 80

16 represents a disk shaped cover having a cylindrical projection 20, the height of which varies according to the position of the wall 18 with respect to the midline —f— of the ring 11. The projection 20 completes 85 together with the projection 17 the inner box so that between the latter and the outer cylindrical wall 1, an annular chamber is formed which at its lower portion is provided with a partition 14. 2 and 3 designate two 90 solid disks having a recess placed eccentrically near the outer periphery, to receive the hub 19 of the member 11 and extremity of the crankshaft 6 passing through this hub. 95

The ring 11 connected by means of the diaphragm 18 to the hub 19 is the swinging piston.

The ring 11 is slotted at 12 according to a generatrix of its cylindrical surface. This 100 slot is expanded to form an opening 13 formed in the diaphragm 18 the outline of this opening being interrupted at the slot to permit of the ring and diaphragm being straddling the partition 14. The shape of 105 the outline of the opening 13 is such that during the swinging of the ring 11, said outline still has a point of contact while slip-

ping thereon with the upper edge 15 of the partition 14.

The partition 14 is of curvilinear section: the curve of the surface of each of its side walls is determined as the series of points of contact of the partition with the adjacent edge of the slot 12, during the oscillation of the piston.

Some constructional alterations could be devised, which however do not modify the essence of the invention. For instance the bushing might be arranged in the cover, or two bushings might be provided, one in the cover and one in the barrel in case it should be desired to adapt a complete crank-shaft in lieu of the crank shown, as may be required by the size of the engine. In the like way any suitable arrangement can be used for the adjustment of the crank support in the bushing 5 in order to compensate for any wear and preserve the requisite tightness, though the perfect balance of the motion will reduce the wear to a minimum and the engine running is such that the fitting of a stuffing-box on the projecting portion of the crank will generally be found unnecessary.

A further important modification would consist in substituting for the point 15 (Fig. 1) two points by means of a curved member equal in thickness to the partition wall of the swinging piston.

The area of the window 13 would thus be increased and this might be advantageous when fluids of greater density must be dealt with and when it is desired to alter the velocity imparted to the same.

Further, if the construction of the engine should make it desirable, the crank-shaft could be made stationary and the barrel rotated in its stead, the working remaining the same.

On reference to the drawing it will be understood how the fluid distribution is effected when the crank-shaft is rotated. Let us assume the crankshaft to revolve in the direction shown by arrow in Fig. 2 and the engine to start moving when the swinging body is in the position shown in Fig. 1. In the portion comprised between the larger inner cylindrical surface of barrel 1, the outer cylindrical surface of the swinging body 11 and the partition 14 a space will result that will increase up to full aperture of the window 7 and will afterward decrease till the said window is closed when the swinging body will pass again through the starting position assumed above. During this phase of the distribution the fluid has entered through window 7 into the barrel 1 and at the same time an equal volume of fluid will have been forced out through the window 8 on the opposite side of partition 14.

This takes place on the outer side of the

swinging body, while on the inner side the same occurs, with the only difference that when the outer portion is on the dead center the inner portion is in its maximum work position, the consequence being a practically constant flow of the liquid through the engine.

Also the hollow space of the window 13 is filled with fluid and emptied at every revolution, and is thus performing a useful work too.

The outline of the inlet and outlet openings 7 and 8 is generated by two arcs of circle, the center of one arc lying on the center line of the crank when the latter is in its lowest position while the center of the other arc lies on the center line of the crank when the crank is in its top-most position, and the radius of the former arc being equal to or smaller than the maximum radius of the swinging body while the radius of the latter arc is equal to or smaller than the minimum inner radius of the said body.

Two further examples of application of this distribution are shown in section in Figs. 5 and 6.

In the engine according to Fig. 5 the partition corresponding to 14 in Fig. 1 is arranged to slide in vertical direction due to a weight or spring not shown on the drawing and is made to always bear against the piston. In the engine according to Fig. 6 the said partition is connected to the piston and in the remaining parts works just as the engine described.

These two constructions too, however, never had a practical interest because of the serious defect of the fluid inlet and outlet communicating with each other at the piston dead center.

In Figs. 5 and 6 the novel distribution may be clearly seen as applied to these engine types.

In the barrels the opening 7'-8' and 7"-8" respectively are formed, whose outline is determined in the same manner as that of the opening 7 and 8 of the engine described above, with the only difference that in these two cases only the radius of the piston periphery comes into consideration because only the outer portion of the piston is working.

The position of these two openings is similar to that of the first engine described. The continuous separation of the ingoing and outgoing fluid is also effected in a similar manner, and the advantage is likewise preserved that ample inlet and outlet areas can be designed, which could not be realized in these engines without the novel distribution because otherwise the inherent drawback of such engines, viz. the communication between the fluid inlet and outlet, would have been increased at the same time.

In order to increase the efficiency of the described engine, the hollow central cylindrical portion should be so filled with a solid or non-solid, metallic or non-metallic 5 part as to prevent the presence of air.

This object can be accomplished, for instance in the engine according to Figs. 1 and 2, where the filling parts are those numbered 2 and 3. In case the flat wall 10 porting the swinging body should be shifted close against the cover, the latter is reduced to a plain flat surface. In lieu of a bushing, as shown in the drawing, the flat wall is provided with a solid journal. In- 15 stead of a crank, a cylinder solid with the engine shaft is arranged, and a recess formed at the required distance from the center accommodates the said journal.

Having now described my invention and how the same is to be carried out, what I 20 claim as my invention is:

1. In a rotary engine or pump, a barrel having two chambers, a cover therefor, an- nular ribs projecting from the barrel and the cover, a shaft in the barrel and provided 25 with a crank and a crank pin, a ring re- ceived in the barrel having a diaphragm and a hub for receiving the crank pin, and solid disks arranged within the space inclosed by the ribs and having eccentric openings for 30 receiving the hub of the ring.

2. A rotary engine or pump as claimed in claim 1 wherein the crank and crank pin are formed integral with one of the disks.

MINO PELIZZOLA.
